INVENTOR:

Cora A. Gooding.

UNITED STATES PATENT OFFICE.

CORA A. GOODING, OF BROOKLINE, MASSACHUSETTS.

DESIGN FOR A SPOON.

SPECIFICATION forming part of Design No. 24,659, dated September 10, 1895.

Application filed December 24, 1894. Serial No. 532,887. Term of patent 7 years.

To all whom it may concern:

Be it known that I, CORA A. GOODING, a citizen of the United States, residing at the town of Brookline, in the county of Norfolk and State of Massachusetts, have invented and produced a new and original Design for a Spoon, of which the following is a specification, reference being had to the accompanying drawing, forming a part thereof.

10 The leading features of my design for a spoon are, first, the handle at its outer end, which represents a person's head—for instance, a player of foot-ball—and a sweater, consisting of the collar, shoulder, and breast portions, 15 and, second, the bowl in the outline or form of a foot-ball, and has the line of the seam and lacing of a foot-ball indicated on it and along its length, the same being provided with a handle having the configuration shown and de- 20 scribed.

The figure of the drawing is a face view of a spoon embodying my design.

In the drawing, A is the bowl, and B is the handle of the spoon. The bowl A is in the outline or form of a foot-ball, and along its 25 length is a representation, as at a, of the seam and, as at b, of the lacing of a foot-ball. At the outer end of the handle B is the configuration of the head C of a person—for instance, a player of foot-ball—and of the collar D, 30 shoulders E, and breast F of a sweater.

What I claim is—

The design for a spoon substantially as shown and described.

CORA A. GOODING.
